Patented Sept. 12, 1911.

UNITED STATES PATENT OFFICE.

ARTHUR BURTON, OF WHITESBORO, TEXAS.

BURNER.

1,003,329.

Specification of Letters Patent. Patented Sept. 12, 1911.

Application filed March 9, 1910. Serial No. 548,166.

To all whom it may concern:

Be it known that I, ARTHUR BURTON, a citizen of the United States, residing at Whitesboro, in the county of Grayson and State of Texas, have invented new and useful Improvements in Burners, of which the following is a specification.

The invention relates to an improvement in hydro-carbon lamps and particularly to an apparatus in which the hydro-carbon oil is delivered under pressure to the burner for ignition, the pressure medium, such as air or the like, being carbureted and delivered to the lamp for initial ignition and vaporization of the oil.

The main object of the present invention is the provision of means whereby the body or hydro-carbon oil is subjected to a determinate air pressure and said oil and air delivered to the carbureter, the carbureted air being subsequently delivered to the burner for initial ignition and the oil from the carbureter finally delivered to the burner and vaporized under the weight of such initial ignition.

A further object of the invention is the provision of a vaporizing tube disposed to the maximum height from the burner and utilized as a support for the mantle at the burner.

The invention in its preferred details of construction will be described in the following specification, reference being had particularly to the accompanying drawings, in which:

Figure 1 is a vertical, sectional view, partly in elevation, illustrating the improved apparatus. Fig. 2 is an enlarged, vertical, sectional view of the burner.

Referring particularly to the accompanying drawings, the improved apparatus comprises a supply tank 1 adapted to receive the desired quantity of hydro-carbon oil, as gasolene or the like, said tank being closed and provided in its top with a filling opening 2 and with a pipe section 3 whereby air may be delivered to the interior of the tank from any desired source to provide the required interior pressure.

An oil supply pipe 4 is arranged within the tank having its lower open end slightly above the bottom of the tank, said pipe beyond the tank being provided with a valve 5 and being extended to and projected with in a carbureter 6, the pipe 4 terminating slightly above the bottom of the carbureter.

The carbureter 6 is preferably in the form of a closed tank and may, if desired, be transparent whereby the height of the liquid within the tank may be observed. In 60 the absence of such transparent wall the carbureter is to be provided with any desired form of device for indicating the height of the liquid therein.

An air supply pipe 7 extends within the 65 supply tank 1 terminating slightly below the top of said tank, and extending behind the tank to and with the carbureter, terminating slightly above the bottom of the latter. A valve 8 is arranged in the pipe 7 70 whereby said pipe may be closed at pleasure. The tank 1 is also provided with a pressure indicator 9 to indicate at all times the pressure within the tank. A liquid supply pipe 10 extends from the carbureter to the 75 burner, said pipe having its open, lower end arranged slightly above the bottom of the carbureter, and a vapor supply pipe 11 also extends from the carbureter to the burner having its open end terminating slightly 80 below the top of the carbureter.

The burner comprises the usual base 12 which is preferably supported by the burner nipple 15, said base comprising the usual plate 13, and depending cylindrical housing 14, the housing 14 having openings through sides and bottom for inlet of air. The burner nipple 15, is secured to and supported by needle-valve (without number in drawing) which needle-valve is supported 85 by end of liquid supply pipe 10. The burner-nipple 15, is provided with a depending section 16, having a downwardly flaring opening 17. And below and in alinement with the section 16, I arrange a 90 sleeve 18 supported from the nipple 15, by branches 19. Within the sleeve 18 is mounted a valve nozzle 20 having a needle opening 21 at its upper end controlled by the usual needle valve 22, the nozzle being 100 preferably held within the sleeve 18 by a set screw 23.

The needle opening 21 of the nozzle is directly in vertical alinement with the opening 17 in the projection 16, and spaced from the end of the said projection to provide for the mixture of the air with the vapor before the latter reaches the burner. The oil supply pipe 10 is, at its juncture with the burner base, in open communication with 105 the vertical projected pipe section 24 which, by means of a suitable coupling, is connect- 110

ed in communication with one leg of an inverted U-shaped vaporizing tube 25, the remaining leg of which is connected to and in communication with the vapor tube 26 which extends through the plate 13, through the sleeve 18 and end and in communication with the nozzle 20. The vaporizing tube 25 is thus projected in inverted U-form above the burner 15, and in such position is adapted and designed to support the upper end of a mantle 27 designed to coöperate in the usual manner with the burner 15. The air vapor tube 11 leading from the carbureter extends to and through the burner 15, said pipes 10 and 11 being provided adjacent the burner with controlling valves 28 and 29.

In use the desired quantity of gasolene is placed in the tank 1 and pressure applied thereon by forcing air into the tank. The valve 5 is then opened to admit the desired quantity of the oil to the carbureter, whereupon the valve is closed. The valve 8 is then opened to admit air under pressure to the carbureter, such air, as will be obvious, being forced through the body or liquid in the carbureter. The valve 29 is then opened and the carbureted air admitted to the needle of the burner and ignited. The valve 28 is then opened and the oil under pressure of the air will be delivered to the vaporizing tube and vaporized by the heat from the burner and the vapor delivered to the point of ignition through a manual control by the valve 22.

Constant supply of the fuel to the burner is thus provided for by a simple means of increasing the pressure on the body or li-

uid within the tank 1, the vapor supply tube 11 being if desired left open to provide a continuous supply of carbureted air to the burner whereby to further enrich the mixture and secure increased brilliancy of the light.

It is of course to be understood that the tubes 10 and 11, which are the connecting means between the supply apparatus and the burner, are comparatively small and may be of any desired length so as to locate the burner remote from the tanks or immediately adjacent thereto as may best suit the particular conditions under which the lamp is to be used.

Having thus described the invention, what is claimed as new, is:—

In a hydrocarbon burner, the combination with a base plate, of a nipple integrally formed therewith, said nipple being provided with a slotted opening, a centrally depending section integrally formed with said base plate, said section being provided with a flaring opening, depending arms integrally formed with said base plate, a sleeve supported by said arms, a nozzle removably supported within said sleeve and in alignment with said depending section, a vaporizing tube in communication with said nozzle, and a needle valve within said nozzle, substantially as and for the purpose as set forth.

In testimony whereof I affix my signature in presence of two witnesses.

ARTHUR BURTON.
